UNITED STATES PATENT OFFICE.

CHARLES H. FRYBARGER, OF CARLTON, COLORADO.

SHIELD FOR LIGHT ARTILLERY.

SPECIFICATION forming part of Letters Patent No. 624,640, dated May 9, 1899.

Application filed April 20, 1898. Serial No. 678,278. (No model.)

To all whom it may concern:

Be it known that I, CHARLES H. FRYBARGER, a citizen of the United States, residing at Carlton, in the county of Prowers and State of Colorado, have invented a new and useful 5 Shield for Light Artillery, of which the following is a specification.

My invention relates to field or light artillery, and has for its object to provide guns of 10 this class of artillery with shields to protect the gunners against bullets while in action.

With this object in view my invention consists in providing a field-gun with a bullet-proof shield which can be adjusted in front 15 of the gunner to protect him from the bullets of the enemy and may be readily turned to rest upon the top of the gun when not in use.

My invention further consists in the improved construction, arrangement, and combination of parts hereinafter fully described, and afterward specifically pointed out in the appended claims.

In order to enable others skilled in the art to which my invention most nearly appertains 25 to make and use the same, I will now proceed to describe its construction and operation, reference being had to the accompanying drawings, forming part of this specification, in which—

30 Figure 1 is a perspective view of a field-gun equipped with a shield constructed in accordance with my invention, part of one of the wheels being broken away to better illustrate the shield. Fig. 2 is a view in side elevation, 35 the axle being shown in section and the shield in dotted lines in its folded or transportable position. Fig. 3 is a top plan view of the shield and its attaching means.

Like letters of reference mark the same 40 parts wherever they occur in the different figures of the drawings.

In referring to the drawings by letters only 45 so much of the gun will be referred to as is necessary to illustrate the application of my invention thereto.

A indicates a gun; B, the carriage; CC, the wheels, and D the axle. All of these parts may be of the usual and ordinary construction, provided the axle, just inside of the 50 wheels, be formed square, as illustrated most plainly in Fig. 2 at D'. About this square portion of the axle, inside of the wheels, is a

clip E, embracing the axle, the threaded ends of which pass through bolt-holes in a plate F, lying against the under side of the axle, 55 and are secured by nuts E'.

The plates F are extended, as at F', in front of the axle, and they are provided on their upper surfaces at a short distance in front of the axle with perforated lugs G G. 60

If indicates a shield which may be made of a single piece of sheet or plate metal sufficiently heavy to resist bullets or of any desired number of pieces of such metal riveted or otherwise secured together. This plate is 65 provided with an elongated notch or slot I, centrally located and extending from the lower edge of the plate to or perhaps slightly beyond its mid-height, the upper or inner end of the slot being curved, as shown in Fig. 1. 70 Near each side narrow vertical slots J are formed in the plate, through which extend the outer ends of branches K' and K" of arms K, pivotally connected to the plates F between the lugs G by means of bolts L, the outer ends 75 of the branches being secured in the slots by means of nuts K'. The plate may be secured to the outer ends of the branches K' and K" of the arms K at any desired height within the limit of the notches J, so that with the arms 80 K and branches K" resting upon the forward extensions F' of the plates F the lower edge of the shield-plate may be always kept clear of the ground, such vertical adjustment being rendered necessary by the unevenness of 85 the ground encountered from time to time.

When the gun is out of action, the shield is turned upon bolts L as pivots until it is brought into the horizontal position illustrated in dotted lines in Fig. 2, and resting upon 90 the top of the gun. Its weight will usually hold it in this position; but, if desired, means may be used to rigidly secure it against any liability to drop into its active position while the gun is being hauled from place to place. 95

The utility of my invention will be readily understood from the foregoing description of its construction and operation. By means of it the gunners may be protected while operating the gun against the fire of sharp-shooters 100 in the front, thus relieving them from a very large percentage of the danger to which they are now exposed, and consequently tending to a more efficient handling of the gun, as well

as greater accuracy and the saving of the lives
of the gunners.

While I have illustrated and described what
I now consider efficient means for carrying
out my invention, I do not wish to be under-
stood as limiting myself to the exact details
of construction shown and described, but hold
that such slight changes or variations as might
suggest themselves to the ordinary mechanic
would properly fall within the limit and scope
of my invention.

Having thus fully described my invention,
what I claim as new, and desire to secure by
Letters Patent of the United States, is—

15 1. The combination with the gun, its car-
riage, wheels and axle, of the plate F secured
to and projecting in front of the axle, the
shield-plate slotted to permit of its being
passed over the gun, and the arms connected
20 to the shield-plate and pivotally connected to
the plate F, substantially as described.

2. The combination with the field-piece, its
carriage, wheels and axle, of clips embracing
the axle, plates secured to the under side of

the axle by said clips and projecting in front 25
of the axle, perforated lugs on the upper face
of said clips, arms pivoted between said lugs,
and the shield-plate, slotted to permit its pas-
sage over the gun and adjustably connected
to the arms, substantially as described. 30

3. The combination with the gun, its car-
riage, wheels and axle, of the shield-plate,
provided with a central elongated notch or
slot reaching from its lower edge to and
slightly beyond its mid-height, and parallel 35
slots near its sides, plates rigidly secured to
the under side of the axle and projecting in
front thereof, perforated lugs on the upper
side of said plates near the axle, arms pivoted
between said lugs and provided with branches 40
projected through the parallel edge slots of
the shield-plate, and means for adjustably se-
curing the branches in said notches, substan-
tially as described.

CHARLES H. FRYBARGER.
